UNITED STATES PATENT OFFICE.

SIEGMUND LUBIN, OF PHILADELPHIA, PENNSYLVANIA.

SYNCHRONIZING APPARATUS.

1,116,453.

Specification of Letters Patent. Patented Nov. 10, 1914.

Application filed March 5, 1913. Serial No. 431,442.

To all whom it may concern:

Be it known that I, SIEGMUND LUBIN, a citizen of the United States, residing in the city of Philadelphia, county of Philadelphia, and State of Pennsylvania, have invented certain Improvements in Synchronizing Apparatus, of which the following is a specification.

My invention is a synchronizing apparatus designed primarily for use in harmonizing the actions of phonographs and kinetoscopes so that related pictures and sounds may be properly coördinated.

It is the leading purpose of my invention to produce an apparatus of improved character which will orally signal the operator that the speed of the manually operated kinetoscope is either too fast or too slow, as well as visually indicate the relation between the pictures and words of the two instruments.

The characteristic features of my improvements are fully disclosed in the following description and the accompanying drawings in illustration thereof.

In the accompanying drawings, Figure 1 is a view illustrating my invention diagrammatically; Fig. 2 is a view of the circuit making and breaking apparatus with parts broken away; Fig. 3 is a side elevation of the apparatus shown in Fig. 2; Fig. 4 is a partial sectional view taken on the line 4—4 of Fig. 2; and Fig. 5 is a partial sectional view illustrating the relation of contacts to the revoluble circuit making and breaking disk.

The mechanism comprises the phonograph 1 having the revoluble shaft 1^b which carries the disk 1^c. This shaft has fixed thereon the spur gear 1^d which engages and revolves a pinion 1^e on a shaft 1^f revolved at several times the speed of the shaft 1^b. On the shaft 1^f is a commutator comprising the cylinder 1^g, insulated from the shaft 1^b and having set in the recess 1^h thereof the cylindrical segment 1ⁱ, insulated from the shaft 1^b and the body of the cylinder 1^g. A contact brush 4 bears on the cylinder so that as the latter revolves the brush makes contact alternately with the body of the cylinder and the section 1ⁱ insulated therefrom. A contact brush 5 bears on the body of the commutator cylinder and by the revolution thereof is electrically con-

nected and disconnected, alternately, with the brush 4.

A source of electric energy, as the battery 6, is connected by a conductor 7 with the contact brush 4 and by the conductors 8, 9, 10, 11 and 12 with the contact brush 5, the conductor 12 containing the switch 13. The conductors 10 enter into the electro-magnets 14 which, with the conductors 9 and 11, are carried by a metal base plate 15 from which the plates 9 and 11 are separated by insulation 15'. An armature 16 has one end pivoted by means of a stud 17 on the plate 15 and the other end connected by means of a coiled spring 18 with a bolt 19 which is held in adjustable relation to the post 20 on the plate 15, posts 21 on the plate limiting the arc of oscillation of the armature, which lies between them. An arm 22, fixed on the armature and extending transversely thereto, has pivoted thereto a pawl 23 pressed by a spring 24. A ratchet wheel 25, engaged by the pawl 23, is fixed on a vertical spindle 26 which is revoluble in the bearings 27 and 27' fixed on the plate, the spindle revolving a conducting indicating bar 28 fixed thereto. A pawl 29, pivoted by means of a post 30 on the plate 15 and pressed by a spring 31 fixed to the plate, engages the ratchet wheel 26 to prevent it and the indicator bar from moving backward.

A kinetoscope 32 has its shaft 33 (which is revolved by the handle 34) connected through the gears 33' and 35' with the shaft 35. The shaft 35 is connected by a flexible shaft 35^a with the worm shaft 36, which is journaled in the bearings 37 on the plate 15. The worm shaft 36 engages the worm wheel 38, which is journaled by means of the post 39 on the plate 15, a pinion 40 being fixed to the worm wheel and revolved thereby. The pinion 40 engages a gear wheel 41 which is revoluble on the spindle 26 and has fixed thereto the graduated disk or dial 42 having its body made of insulating material. Metal rings 43 and 44 are secured to the respective faces of the disk with their outer edges in the periphery thereof, the rings being electrically separated. Within a segmental recess 45 formed in the ring 44, are ring segments 46 and 47 insulated from the ring 44 and from each other, a screw 48 electrically connecting the segment 46 with the ring 44. The indicator

bar 28 has a contact piece 49 connected with an end thereof by the pins 50 which are movable through the bar, the piece 49 being held down by springs 51 and adapted for making contact with the parts 44, 46 and 47.

A post 37 has thereon an insulating block 52 to which is secured contact brushes 53 and 54 which engage the rings 43 and 44. A source of electric energy, as a battery 55, 10 is connected by the conductors 56, 57, 58 and 59 with the contact 53; by the conductors 56, 60, 61 and 62 with the contact 54, and by the conductor 63 with the plate 15; the conductor 57 containing the bell 64, the conductor 60 containing the buzzer 65, the conductor 63 containing the switch 66, and the conductors 58 and 61 being separated from the plate 15 by the insulation 15'.

It follows from the foregoing construction 20 that when the phonograph is in operation and the switch 13 closed, the commutator revolving in engagement with the contacts 4 and 5 will alternately make and break the circuit containing the electro-magnets 14, 25 which, when the circuit is closed, draw the armature 16 thereto and when broken permit the spring 18 to draw it therefrom. Hence the armature, acting through the arm 22 and the pawl 23 thereon, revolves the 30 ratchet wheel 25 and the indicator bar 28 in synchronism with the action of the phonograph. When the switch 66 is closed and the contact 49 engages the ring segment 46, the circuit containing the bell 64 is closed 35 by the connection of the conductors 59 and 63 through the electrically connected parts 53, 43, 48, 46, 49, 50, 28, 26, and 15. When the contact 49 engages the ring 44, the circuit containing the buzzer 65 is closed by the 40 connection of the conductors 62 and 63 through the electrically connected parts 54, 44, 49, 50, 28, 26, and 15. When the contact 49 engages the ring segment 47, the point of the bar being at the zero point of 45 the dial formed by a graduated scale on the disk, the circuits containing the bell and buzzer are both broken. Therefore the op-

erator handling the kinetoscope will have an oral signal informing him when he is operating the kinetoscope either faster or 50 slower than the phonograph, it being the purpose to have the disk or dial and the indicator bar register at the zero point and travel at the same speed when the rate of the phonograph and kinetoscope deliver their 55 oral and visual subjects in harmony.

It will be understood that if the synchronizing instrument is not properly calibrated so that the indicator bar and dial do not register at the zero point when the kinetoscope and phonograph run in harmony, when they are run in harmony the scale will 60 show the error and by means thereof the calibration may be effected.

Having described my invention, I claim: 65

The combination with a kinetoscope and a phonograph, of synchronizing apparatus comprising a disk operated by one of said devices and an indicator operated by the other of said devices and adapted to move 70 over the face of said disk, said indicator and disk co-operating to indicate the relative operation of said devices, a pair of conducting ring segments carried on the face of said disk and adapted to be engaged by said indicator, said segments being insulated from each other, peripheral conducting rings on said disk and connected with the respective ring segments, a circuit comprising contacts 75 engaging the respective peripheral rings and a conductor connected with said indicator, and signaling mechanism controlled by said circuit, said signaling mechanism being operated upon the closure of said circuit 80 by the engagement of said indicator with one of said ring segments.

In witness whereof I have hereunto set my name this 1st day of March, 1909, in the presence of the subscribing witnesses.

SIEGMUND LUBIN.
